United States Patent Office

Des. 175,478
Patented Aug. 30, 1955

175,478

LAMP BASE OR SIMILAR ARTICLE

George M. Passwater, Newport, R. I.

Application February 11, 1955, Serial No. 34,481

Term of patent 14 years

(Cl. D48—20)

Figure 1 is side elevational view of a lamp base or similar article, showing my new design, and

I claim:

The ornamental design for a lamp base or similar article, substantially as shown.
